ELECTRIC STOCK PROD

Harold W. Darr, Minneapolis, Minn., assignor to Hot Shot Products Co., Minneapolis, Minn., a corporation of Minnesota

Application December 7, 1954, Serial No. 33,432

Term of patent 14 years

(Cl. D12—2)

Fig. 1 is a view in plan of an electric stock prod showing my new design;

Fig. 2 is a view in side elevation;

Fig. 3 is a fragmentary view in bottom plan;

Fig. 4 is an end elevation as seen from the left to the right with respect to Fig. 2, on an enlarged scale;

Fig. 5 is a view in end elevation as seen from the right to the left with respect to Fig. 2; and

Fig. 6 is a fragmentary section taken on the line 6—6 of Fig. 2.

The side opposite that shown in Fig. 2 is devoid of the rectangular plane surface shown in Figs. 2 and 6.

I claim:

The ornamental design for an electric stock prod, as shown and described.
